Fig. 4

Fig. 5

FIG. 1 is a front perspective view of a combined bank drive-up counter and window showing my new design;

FIG. 2 is a rear perspective view of the combined bank drive-up counter and window of FIG. 1;

FIG. 3 is a left end elevation of the combined bank drive-up counter and window of FIG. 1;

FIG. 4 is a front elevation of the combined bank drive-up counter and window of FIG. 1;

FIG. 5 is a rear elevation of the combined bank drive-up counter and window of FIG. 1; and

FIG. 6 is a vertical sectional view, looking in the direction of the arrows 6-6 in FIG. 5.

I claim:

The ornamental design for a combined bank drive-up counter and window or similar article, substantially as shown.
